TRANSMISSION SUBSTITUTION SYSTEM

John C. Walter, Collingswood, N. J., assignor to
Wired Radio, Inc., New York, N. Y., a corpora-
tion of Delaware

Application October 3, 1936, Serial No. 103,922

7 Claims. (CL. 179—15)

My invention pertains in general to signal transmission systems and specifically relates to a multiple transmitter organization.

The principal object of the invention consists in providing a transmitting organization providing means for automatically rendering a spare transmitter effective in the event of an overload in the transmitting organization.

A further object of the invention comprises providing a group of signal transmitters and an auxiliary stand-by signal transmitter common to said group of transmitters with means for automatically associating said stand-by transmitter with the circuits of any one of the transmitters of said group to replace the function of that transmitter in the group.

A further object of the invention comprises providing a wired radio distribution system having means for simultaneously transmitting a plurality of programs over a common transmission medium with stand-by transmission means rendered automatically effective in an emergency.

A further object of the invention resides in the disposition and details of automatic circuits and protective circuits incorporated in the system.

In the drawings which accompany and form a part of the specification, and in which like reference numerals designate corresponding parts:

Fig. 1 is a schematic representation of an electrical transmission organization in accordance with one embodiment of the invention;

Fig. 2 is a diagrammatic representation of a control circuit employed in the system of Fig. 1;

Fig. 3 is a schematic representation of protective circuit of the system of Fig. 1; and

Fig. 4 is a graphical representation showing the relative operative positions of a switch system employed in the organization of Fig. 2.

General transmission organization

Referring to the drawings in detail, lines 1 represent three-phase program lines which are coupled with the commercial alternating current distribution feeders in a wired radio distribution system. Filters 2, 3 and 4 are connected with the lines 1. These filters comprise networks for passing carrier frequencies within discrete frequency bands corresponding to different wired radio program channels. For example, the filters 2, 3 and 4 may pass side band frequencies within the ranges of carrier frequencies of 26 kilocycles, 39 kilocycles, and 52 kilocycles, respectively. These carrier frequency ranges correspond to individual program "channels", designated as channels A, B and C, each comprising a separate pro-

gram modulation, and all transmitted simultaneously.

An input circuit to the filter 2 is connected with two movable contactors 7 and 8. The input circuit to filter 3 is connected with movable contactors 9 and 10, and the input circuit to filter 4 is connected with movable contactors 11 and 12. These movable contactors, when in a right hand position as shown in Fig. 1, complete circuits from high power amplifiers 13, 14 and 15 to the filters 2, 3 and 4, respectively. The movable contactors for each program channel are adapted to be moved to a left hand position by transfer solenoids 16, 17 and 18, respectively.

The high power amplifiers 13, 14 and 15 are controlled by the output from low power amplifiers 19, 20 and 21, respectively. Movable contactors 22 and 23 are connected with the output circuit of an A channel program source 24, and, when in a right hand position as shown in Fig. 1, complete a connection from the source 24 to the low power amplifier 19. Movable contactors 25 and 26 are connected with the output of a B channel program source 27 and, when in a right hand position as shown in Fig. 1, complete a circuit from the source 27 to the low power amplifier 20. Similarly, movable contactors 28 and 29 are connected with the output of a C channel program source 30 and, when in a right hand position as shown in Fig. 1, complete a circuit with the input of low power amplifier 21.

The program sources 24, 27 and 30 are indicative of separate studios including suitable amplification and modulation equipment for producing the necessary modulated program frequencies to be amplified over the low power and high power amplifiers. Rectifier units 40, 41 and 42 are individually associated with the amplifiers of the three program channels, and control units 43, 44 and 45 are also individually associated with the equipment of each channel. The rectifier units comprise means for supplying the necessary operating voltages to the amplifiers, and the control units include meters and relays associated in the controlling operations for each channel.

Auxiliary transmission equipment

An auxiliary transmitter unit is provided and includes a high power amplifier 47, low power amplifier 48, a rectifier unit 49, and a control unit 50. These units correspond to the similar units of the channels A, B, and C. All of the transmitters are of the untuned anode circuit type.

In one aspect of the invention, the amplifiers 47 and 48 may be provided with circuit systems 53

respectively operative for amplifying the frequencies of the individual program channels. These different circuit systems are rendered individually effective by relays 51, 52 and 53. Closing of relay 51 completes the circuit through selected parameters of the amplifiers to most efficiently amplify the frequencies within the range of filter 2. Closing of relay 52 controls the amplifiers to operate similarly with respect to frequencies of filter 3, and the closing of relay 53 will operate to effect the amplifiers to most efficiently amplify the frequencies within the range of filter 3. The relays 51, 52 and 53 are respectively energized by circuits extending through switch contactors 54, 55 and 56. The contactors 54, 55 and 56 are respectively controlled by solenoids 16, 17 and 18, so that the energization of any one of these solenoids will effect the corresponding one of the relays 51, 52 or 53. This arrangement of frequency conditioning of the auxiliary equipment is for optional use.

Transfer circuit system

The contactors 22 and 23 may be moved into a left hand position by transfer solenoid 36. The contactors 25 and 26 may be moved into a left hand position by transfer solenoid 37, and the contactors 28 and 29 may be moved into a left hand position by transfer solenoid 38. Contactors 31 and 32 are positioned to be moved away from their associated contactors upon energization of solenoid 36. Armatures 33 and 34 are positioned to be moved away from their associated contactors upon energization of solenoid 37, and contactor 35 is positioned to be moved away from its associated contactor upon energization of solenoid 38.

Solenoids 16 and 36 are connected in parallel and include a connection through a switch 60a-99a to the rectifier unit 40. The solenoids 17 and 37 are connected in parallel and include a circuit through switch 60b-99b to rectifier unit 41; and the solenoids 18 and 38 are connected in parallel and include a circuit through switch 60c-99c to rectifier unit 42.

The other side of the circuit to solenoids 16 and 36 includes a connection to the normally closed contactor 33, this contactor being connected through contactors 31 and 35, as shown. The other side of the circuit to solenoids 17 and 37 includes a connection to contactor 31, and the other side of the circuit to solenoids 18 and 38 includes a connection to contactor 34. Contactor 32 includes a connection to contactor 34, and the other side of contactor 32 is connected with contactor 35 and thence to a common circuit including the rectifier units 40, 41 and 42, as shown.

Typical control circuit

By way of illustration, a typical transfer control circuit will be described as used in channel A with rectifier unit 40. Referring to Fig. 2, terminals 70 are connected with the commercial alternating current supply, such as 220 volts, 60 cycles. Terminals 71 are connected with the primary of the high voltage anode current supply transformer included in the rectifier unit.

Current transformers 72 and 73 are associated with the lines leading through contactors 74, 75, and 76 to the terminals 71. The transformers 72 and 73 are included in circuits through instantaneous solenoids 81 and 82. The solenoids 75 81 and 82 which control contactors 86 and 87

include an energizing circuit extending to a relay 78 and stepping magnet 79. Upon opening of the contactors 86 and 87, the energizing circuit to solenoid 78 and magnet 79 is broken, whereupon the relay 78 opens the energizing circuit to a solenoid 80.

Deenergization of solenoid 80 opens the contactors 74-76, whereupon the current supply of the channel "A" transmitter is interrupted. The interruption of the energization circuit to magnet 79 permits a spring to move the pawl armature 90 to engage a six-toothed ratchet 91 and advance the same one step. As soon as the contactors 74-76 are released to an open position by the deenergization of solenoid 80, the over-load condition is removed, whereupon energization of instantaneous solenoids 81 and 82 is interrupted. Contactors 86 and 87 are then released to close the circuit to relay 78 and magnet 79.

The ratchet 91 is moved in a counter-clockwise direction by the pawl-armature 90 against a torsion spring. A dog-armature 92 is normally held in engagement with the teeth of ratchet 91 to prevent the ratchet from turning in a clockwise direction until the armature 92 is actuated by a release magnet 93. The shaft of ratchet 91 carries cams 94, 95, 96, which respectively operate contactors 97, 98 and 99. One complete revolution of the ratchet 91 comprises a cycle of operations for the cams 94-96 and their respective contactors 97-99.

The cams 94-96 have peripheral configurations such as to produce the switching operations depicted in the table of Fig. 4. The shaded areas in the table of Fig. 4 indicate the duration of an upward contacting position of the contactors 97-99 for the six consecutive positions of the ratchet 91, beginning with the first position just described in connection with the interruption of the energizing circuit to magnet 79.

When the contactors 74-76 are again closed, and if the over-load condition persists, the solenoids 81 and 82 are again energized, whereupon the contactors 86 and 87 again interrupt the energizing circuit to solenoid 78 and magnet 79. Solenoid 78 again acts to release the contactors 74-76, and the magnet 79 advances the ratchet 91 another step. If the over-load condition persists, the complete cycle of "drop-out" and "reset" operations results, as depicted in the table of Fig. 4. When the ratchet 91 is advanced to its sixth position the contactor 97 is raised to an upward position and the contactors 98 and 99 are lowered. In this position the circuit to relay 78 and solenoid 80 becomes interrupted through contactor 99 and cannot be closed again until the ratchet 91 is reset to its normal starting position. In this sixth position of the ratchet 91, the contactor 99 has been moved to engage contact 60, which controls the energizing circuits to the transfer relays for each channel.

When the ratchet 91 has been advanced to its sixth position, the contactor 97 completes an energizing circuit from the terminal 100 to magnet 93. The terminal 100 includes a circuit extending through a remote switch 101, which may be manually or electrically operated to actuate the dog-armature 92 for releasing ratchet 91 so that the same may be returned to a normal position under action of its torsion spring. When the ratchet 91 is returned to its normal position the cams 94, 95 and 96 will likewise be returned to their initial or starting positions.

It will be noted from the table of Fig. 4 that contactor 98 engages its associated contact dur-

ing all of the intermediate positions of the ratchet 91 between the first and last position. Thus, if the over-load condition on the lines of terminals 71 should be cleared while the ratchet 91 is in an intermediate position, an energizing circuit is completed through the contactor 98 to a heater element 103 of unit 102, which includes a bimetallic switch 104. The unit 102 constitutes a time delay switch, so adjusted that if the ratchet 91

10 remains in an intermediate position for a predetermined period due to the clearing of the over-load fault, the switch 104 will close, due to the heating action of heater 103, whereupon an energizing circuit is established to the release magnet 93, thereby restoring ratchet 91 and its associated switching elements to an initial position.

15 When the over-load fault in a channel, such as channel A, has been removed, the normal transmitter can be restored to operation by manually or electrically closing the switch 101 associated with that channel. When this switch is closed, the signal input and load output circuits are restored to the normal equipment in the channel circuits, leaving the auxiliary transmitter free to accept service on demand from any other channel that may become inoperative.

Transfer operation

20 When, in the sixth position of the ratchet 91, the contactor 99 engages the terminal 60, the transfer solenoids 16 and 36 of channel A will be energized. Energization of solenoid 16 causes the contactors 7 and 8 to be moved into a left hand position, and energization of solenoid 36 causes the contactors 22 and 23 to be moved into a left hand position. When the contactors 7 and 8 are moved thus, the input circuit to filter 2 for channel A is connected with the output of 25 the high power amplifier 47. Similarly, the output of the program source 24 is directed to the input of the low power amplifier 48. As a result of this switching operation, the high power amplifier 13 and low power amplifier 19 become effectively isolated from the active program circuits of channel A. Similarly, the engagement of the switch 99 with the contact 60 in the equipment of any of the other channels will produce a similar result, provided that the auxiliary transmitter 30 is not already in use as an active part of a program channel.

Protective lock-out circuit

Referring to Fig. 3, when the contactor 99a 25 engages terminal 60a for channel A, the solenoid 36 will move the contactors 31 and 32 to a left hand position. This movement of contactor 31 opens the energizing circuit to solenoid 37 so that the same cannot be energized for a transfer operation. At the same time, the left hand position of contactor 32 opens a circuit which extends through contactor 34 to solenoid 38 which prevents energization of solenoid 38 while the contactor 32 is in a left hand position.

30 Similarly, assuming that contactor 99a has not engaged contact 60a, but that contactor 99b has engaged contact 60b, the contactors 33 and 34 will then be moved to a left hand position upon energization of solenoid 37. The contactor 33 will open the circuit to solenoid 36 to prevent energization of that solenoid, and the contactor 34 will open the energizing circuit extending from contactor 32 to the solenoid 38, thereby preventing energization of that solenoid.

35 Again, assuming that contactors 99a and 99b have not been closed, but that contactor 99c has

been closed for channel C, the contactor 35 will then be moved to a left hand position which will interrupt the energizing circuit extending to the transfer solenoids 36 and 37. Accordingly, the energization of the transfer solenoids for any 5 particular channel in a transfer operation will lock out all other channels from further transfer operations, while the auxiliary transmitter is in use in the first channel.

Transfer control circuit function

10

When an over-load fault occurs in a particular channel, the transfer control circuit for that channel, such as typically disclosed in Fig. 2, operates to open the power circuit for a short interval and then reclose the same. If the fault is then cleared, the transfer control circuit is automatically restored to a normal or initial position. In the event that the fault is not cleared upon reclosing of the power circuit, the power circuit is again opened and reclosed. This cycle of operation is continued until the fifth closing operation. Upon the sixth closing operation, if the fault has not then been cleared, the transfer relays are energized and the auxiliary transmitter transferred to the defective or inoperative channel in place of the normal equipment therein. In the event that the fault is cleared during any one of these testing operations of the transfer control circuit, up to its last testing operation, the transfer control circuit is automatically returned to a normal or initial position. When the last testing operation is completed, the transfer operation takes place so that the auxiliary transmitter becomes effective in the required 35 channel. When the proper fault has been cleared, the auxiliary transmitter is restored to a stand-by condition under control of the manual resetting switch connected with the controlling transfer control circuit.

40 Although a preferred form of automatic transfer circuit has been disclosed, it will be recognized that various changes and equivalent organizations can be made without departing from the intended scope of the invention. Therefore, no 45 limitation is intended other than as pointed out in the appended claims.

45 What I claim as new and original and desire to secure by Letters Patent of the United States is:

50 1. A signalling transmission system comprising, a plurality of transmission circuits corresponding to different signal channels and each having transmission equipment connected thereto, auxiliary transmission equipment, and transfer control means having parts in each of said circuits responsive to a circuit fault for disconnecting the transmission equipment in said circuit, and operably substituting said auxiliary equipment therein in a selection operation among 55 said transmission circuits as determined by said fault, said transfer control means including means responsive to an operation by the transfer control means of one of said transmission circuits for preventing the operation of any of the 60 transfer control means in the other of said circuits from effectively operating at subsequent times to appropriate said auxiliary equipment while said auxiliary equipment is operably connected in one of said transmission circuits.

65 2. A transmission system comprising, a plurality of different signal transmission circuits each including a high frequency amplifier and a modulated high frequency source connected thereto, a spare high frequency amplifier, and switching 70

75

- means for disconnecting any one of said amplifiers from its transmission circuit while automatically substituting said spare amplifier therefor, said switching means comprising substitution control-circuit means, by-pass circuits extending from opposite sides of the normal amplifiers of said transmission circuits to connect the modulated high frequency source of a transmission circuit directly through said spare amplifier to by-pass the normal amplifier, and electromagnetic means responsive to currents transmitted over said control circuit means for selectively closing said by-pass circuits to connect said spare amplifier in a transmission circuit.
3. A transmission system comprising, a plurality of high frequency transmission systems with transmitter units having amplifiers tuned to different frequencies, a plurality of frequency selection circuits respectively connected with the output of the units of said transmission systems and individually adapted to pass frequencies within different frequency ranges, an auxiliary transmitter unit including a broadly tuned high frequency amplifier, and automatic switching means operative in response to a current controlled by overload in any one of said transmission systems for disconnecting any one of said transmitter units from its respective selection circuit while conjointly substituting said auxiliary unit therefor.
4. A transmission system comprising, a transmission network, a plurality of filter systems of different frequency characteristics connected with said network, a plurality of signal sources, a plurality of amplifier equipments, controlling transfer means for selectively rendering effective either of two of said equipments between any one of said signal sources and one of said filter systems for transmitting signals through said filter system over said network, said controlling transfer means including circuits responsive to a fault

in one of said equipments connected with a particular filter for substituting another equipment therefor in association with said filter.

5. A transmission system comprising, a plurality of load circuits of different frequency characteristics, means for supplying currents in the event of transmission overload faults associated with said load circuits, a plurality of signal sources, a broadly tuned high frequency amplifier adapted to supply signals within a frequency range embracing all of said circuits, and switching means automatically operated in response to an overload current for selectively coupling said amplifier between selected ones of said signal sources and said load circuits.

6. A transmission system comprising, a plurality of transmission circuits including load circuits of different frequency characteristics, high frequency amplification equipment in each of said circuits, auxiliary high frequency amplification equipment, controlling means appurtenant to each of said transmission circuits and responsive to a fault for producing a predetermined sequence of fault-testing operations, and transfer means responsive to said controlling means upon the completion of said testing operations for disabling said amplifier equipment in the transmission circuit in which the fault occurs, and automatically substituting said auxiliary equipment therefor, said transfer means cooperating with the controlling means of said transmission circuits to selectively substitute said auxiliary equipment in the one of said transmission circuits in which a fault occurs.

7. The transmission system in accordance with claim 6 including a protective arrangement for preventing the auxiliary equipment appropriated for any one of said transmission circuits from being subsequently appropriated by any other transmission circuit in which a fault may occur.

JOHN C. WALTER.
